US00D584726S

(12) **United States Design Patent**
Morita(10) **Patent No.:** **US D584,726 S**
(45) **Date of Patent:** **** Jan. 13, 2009**(54) **PORTABLE INFORMATION TERMINAL
UNIT**D448,764 S 10/2001 Marsalka et al.
D486,823 S 2/2004 Kuo
D487,457 S 3/2004 Liu(75) Inventor: **Fumio Morita**, Tokyo (JP)

(Continued)

(73) Assignee: **Kabushiki Kaisha Toshiba**, Tokyo (JP)

FOREIGN PATENT DOCUMENTS

(**) Term: **14 Years**JP 894474 3/1994
JP 1102866 3/2001
JP 1189159 11/2003
JP 1260942 1/2006
KR 30-0362475 9/2004(21) Appl. No.: **29/304,000**(22) Filed: **Feb. 22, 2008**(30) **Foreign Application Priority Data**

Sep. 21, 2007 (JP) 2007-025755

(51) **LOC (9) Cl.** ..... **14-02**(52) **U.S. Cl.** ..... **D14/341**(58) **Field of Classification Search** D14/341,
D14/342, 343, 344, 345, 346, 347, 420, 426,
D14/427, 432, 439, 440, 441, 448, 496, 125,
